Primary Examiner — Selina Sikder

(74) Attorney, Agent, or Firm — Banner & Witcoff, Ltd.

(57) **CLAIM**

The ornamental design for a remote controller for toilet seat, as shown and described.

DESCRIPTION

FIG. 1. is a front perspective view of a remote controller for toilet seat showing our new design;

FIG. 2. is a front view thereof;

FIG. 3. is a rear view thereof;

FIG. 4. is a left side view thereof;

FIG. 5. is a right side view thereof;

FIG. 6. is a top plan view thereof; and,

FIG. 7. is a bottom plan view thereof.

The broken lines shown represent portions of the remote controller for toilet seat and form no part of the claimed design.

1 Claim, 5 Drawing Sheets
